CLAIM

The ornamental design for a display screen with animated user interface, as shown and described.

DESCRIPTION

FIG. 1 is a front view of a display screen with animated user interface showing the new design; and

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;
FIG. 15 is the fifteenth image thereof;
FIG. 16 is the sixteenth image thereof;
FIG. 17 is the seventeenth image thereof;
FIG. 18 is the eighteenth image thereof;
FIG. 19 is the nineteenth image thereof;
FIG. 20 is the twentieth image thereof;
FIG. 21 is the twenty-first image thereof;
FIG. 22 is the twenty-second image thereof;
FIG. 23 is the twenty-third image thereof;
FIG. 24 is the twenty-fourth image thereof;
FIG. 25 is the first image of a second embodiment thereof;
FIG. 26 is the second image thereof;
FIG. 27 is the third image thereof;
FIG. 28 is the fourth image thereof;
FIG. 29 is the fifth image thereof;
FIG. 30 is the sixth image thereof;
FIG. 31 is the seventh image thereof;
FIG. 32 is the eighth image thereof;
FIG. 33 is the ninth image thereof;
FIG. 34 is the tenth image thereof;
FIG. 35 is the eleventh image thereof;

FIG. 36 is the twelfth image thereof;
FIG. 37 is the thirteenth image thereof;
FIG. 38 is the fourteenth image thereof;
FIG. 39 is the fifteenth image thereof;
FIG. 40 is the sixteenth image thereof;
FIG. 41 is the seventeenth image thereof;
FIG. 42 is the eighteenth image thereof;
FIG. 43 is the nineteenth image thereof;
FIG. 44 is the twentieth image thereof;
FIG. 45 is the twenty-first image thereof;
FIG. 46 is the twenty-second image thereof;
FIG. 47 is the twenty-third image thereof; and,
FIG. 48 is the twenty-fourth image thereof.

The broken line showing of the display screen in both embodiments and of the numbers in the second embodiment is for environmental purposes only and forms no part of the claimed design. The appearance of the image transitions sequentially between the images shown in FIGS. 1-24 and FIGS. 25-48. The process or period in which an image transitions to another forms no part of the claimed design.
